UNITED STATES PATENT OFFICE

JOSEPH J. R. MEYERS, OF NEW YORK, N. Y.

DESIGN FOR A HATCHET

Application filed June 26, 1931. Serial No. 40,336. Term of patent 7 years.

To all whom it may concern:

Be it known that I, JOSEPH J. R. MEYERS, a citizen of the United States, and a resident of the city of New York, borough of Manhattan, in the county of New York, and State of New York, have invented the new, original, and ornamental Design for Hatchets, of which the following is a specification.

Reference is to be had to the accompanying drawing forming a part hereof, in which

The figure is a side view of a hatchet, showing my new design, the opposite side thereof being plain.

I claim:

The ornamental design for a hatchet, substantially as shown and described.

JOSEPH J. R. MEYERS.
